(57) **CLAIM**

The ornamental design for an electronic vaporization device assembly as shown and described.

DESCRIPTION

FIG. 1 is a top, front and left side perspective view of the electronic vaporization device assembly where the first component and second component showing our new design in assembled state of use;

FIG. 2 is a bottom, rear and right side perspective view of FIG. 1;

FIG. 3 is a front elevational view of FIG. 1;

FIG. 4 is a rear elevational view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is a top, front and left side exploded perspective view of the electronic vaporization device assembly of FIG. 1;

FIG. 10 is a bottom, rear and right side exploded perspective view of the electronic vaporization device assembly of FIG. 1;

FIG. 11 is a front elevational view of the electronic vaporization device assembly where the first component removed from the assembly shown in FIGS. 1–10 for clarity of disclosure;

FIG. 12 is a rear elevational view of FIG. 11;

FIG. 13 is a left side view of FIG. 11;

FIG. 14 is a right side view of FIG. 11;

FIG. 15 is a top plan view of FIG. 11;

FIG. 16 is a bottom plan view of FIG. 11;

FIG. 17 is a front elevational view of the electronic vaporization device assembly where the second component removed from the assembly shown in FIGS. 1–10 for clarity of disclosure;

FIG. 18 is a rear elevational view of FIG. 17;

FIG. 19 is a left side view of FIG. 17;

FIG. 20 is a right side view of FIG. 17;

FIG. 21 is a top plan view of FIG. 17; and,

FIG. 22 is a bottom plan view of FIG. 17.

The broken lines in the drawings depict portions of the electronic vaporization device assembly that form no part of the claimed design.
